UNITED STATES PATENT OFFICE.

MEADE FERGUSON, OF RICHMOND, VIRGINIA.

HAT-PIN-POINT PROTECTOR.

1,098,791.

Specification of Letters Patent. Patented June 2, 1914.

Application filed April 29, 1913. Serial No. 764,442.

To all whom it may concern:

Be it known that I, MEADE FERGUSON, a citizen of the United States, residing at Richmond, in the county of Henrico and State of Virginia, have invented new and useful Improvements in Hat-Pin-Point Protectors, of which the following is a specification.

This invention relates to hat pin point protectors; and it has for its object the provision of a device of this character which will include an outer member and an inner member, the latter having an entrance mouth defining portion associated with a similar portion of the outer member and then provided with an effective impinging surface grooved longitudinally and positioned with relation to the adjacent longitudinal walls of the outer member so as to define therebetween a passage for the reception of the point of the pin.

A further object of the invention is the provision of means for facilitating the operation of assembling the two members of the device.

With these and other objects in view, the invention consists of certain novel features of construction, combination and arrangement of parts, as will be hereinafter described and claimed.

In the accompanying drawings:—Figure 1 is a side view of the pin, showing the application of the protector thereto; Fig. 2 is a longitudinal section through the protector; Fig. 3 is a section on line 3—3 of Fig. 2; and Fig. 4 is a section on line 4—4 of Fig. 2.

The protector comprises an outer member 1 having a cylindrical body 2 closed at one end by a spherical portion 3 and open at its outer end, as at 4. At one side the longitudinal walls of the cylindrical portion 2 are extended beyond the open end 4 and then flared outwardly and away from said end, as at 5, so as to define one section of a pin guiding and deflecting mouth 6. The other element or section 7 of the mouth 6 has its walls flared away from the walls of the section 5, and, as shown, the sides of the portion 7 are of a gradually reduced thickness, as at 8, being associated with walls 9 of reduced thickness from the portion 5, so that the passage in the mouth 7 is substantially of an uninterrupted internal formation. The section 7 of the mouth 6 is provided with a longitudinal impinging extension 10

which extends through the cylindrical portion 2 of the outer member and which is preferably of concavo-convex form transversely, the concavity thereof being disposed immediately opposite the adjacent internal curved walls of the cylindrical portion 2, so as to define therewith an intervening pin receiving passage 11. At the extreme outer end the impinging member 10 is provided with an offset 12 having a curved surface 13 mounted on an adjacent internal surface of the spherical end 3, said surface serving as a fulcrum by means of which the impinging member may be rocked with relation to the longitudinal walls of the cylindrical portion 2. The cylindrical portion 2 is provided with internal spaced ribs 14 which receive therebetween a projection 15 on the flared terminal 16 of a spring 17. The opposite end of the spring is secured at 18 by means of solder or the like to the impinging member 10, so as to normally maintain a closed position of the latter with relation to said adjacent walls of the portion 2.

The device may be constructed of porcelain, glass, metal or any other suitable well known material which may be found desirable for the purpose.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as claimed.

Having thus described my invention, what I claim is:—

1. A hat pin point protector comprising an outer member including a spherical portion and a hollow head at one end of the cylindrical portion, the cylindrical portion being open at its opposite end and having a portion of its wall flared outwardly beyond the open end to provide a mouth section, a second mouth section associated with the first section, an impinging member carried by the second mouth section and extending through said cylindrical portion of the outer member and terminating in an outer curved surface mounted for rocking movement on the internal surface of the spherical head, and a spring interposed between the inner wall of the outer member and said imping-

ing member for normally holding the latter closed with relation to the adjacent inner wall of said cylindrical portion.

2. A hat pin point protector comprising an outer member including a cylindrical portion, an inner impinging member extending through the outer member, internal spaced ribs formed in the outer member, and a spring secured to the impinging member and having a locking portion confined between the said ribs whereby to hold the impinging member against longitudinal displacement.

3. A hat pin point protector comprising an outer member having a hollow spherical portion, an inner impinging member having one end seated against the inner wall of the spherical portion and curved to conform with the curvature of said wall, whereby said inner member is mounted for rocking

movement in said outer member, said inner member having a flared wall extending beyond one end of the outer member, the outer member having a flared wall associated with the flared wall of the impinging member and defining therewith an entrance mouth, the impinging member being associated with the adjacent wall of the outer member so as to define therewith a pin receiving passage axially of the mouth, and a spring interposed between the outer member and the impinging member for holding the latter closed with relation to said adjacent wall of the outer member normally.

In testimony whereof I affix my signature in presence of two witnesses.

MEADE FERGUSON.
